UNITED STATES PATENT OFFICE.

EDGAR BOYD KAY, OF WASHINGTON, DISTRICT OF COLUMBIA.

INCINERATOR.

Application filed June 10, 1924. Serial No. 719,144.

The invention described herein may be used by the Government, or any of its officers or employees in prosecution of work for the Government, without payment of any royalty 5 thereon.

This invention relates to a furnace or incinerator and more particularly to a water cooled damper adapted to segregate certain sections of the combustion chamber. While it 10 is shown as applied to an incinerator it is equally applicable to furnaces of a general construction. The object is to provide a simple, durable and inexpensive construction of damper having a hollow metal frame 15 through which a cooling medium is passed to maintain a reduced temperature therein, and reduce the cost of maintenance of one of the most expensive elements of a high temperature furnace.

20 A further object is to provide means whereby the circulating cooling medium may be conveniently supplied to and removed from the damper, without in any way interfering with the operation of the damper which is 25 ordinarily vertically slidable. This and other objects will appear in the following description and will be further pointed out in the appended claims.

Similar numerals of reference indicate corresponding parts in all the figures of the 30 drawings in which:

Fig. 1 is a vertical, longitudinal section of an incinerator showing dampers separating a 35 preheating chamber and a direct draft passage from the remainder of the combustion chamber.

Fig. 2 is an enlarged vertical section taken transversely through one of the dampers.

Fig. 3 is an enlarged elevation of one of the 40 dampers.

Fig. 4 is a detail plan view of the inlet and outlet mounting strut, at the upper end of the damper.

Fig. 5 is a horizontal section through the 45 lower portion of the damper.

Reference now being had to the drawings by numerals 1 represents one form of incinerator to which this improved damper may be applied. The combustion chamber 2 is 50 provided with a means for preheating air to be supplied to certain portions of the incinerator. Said preheating chamber 3 occupies the lower half of the combustion chamber over which extends the direct draft passage.

55 While this improved damper is shown as

applied to a preheating incinerator, merely for illustrative purposes, it, of course, will be understood that a damper of this character is of great value in any high temperature furnace wherein, for instance, throttling the 60 draft is necessary either in a natural draft or forced draft type of furnace and offers the greatest possible protection to the parts that are inclined to be most quickly consumed by said temperature. The construction shown 65 permits quick replacement of the fire brick of the damper, when destroyed.

One of the improved dampers shown in this application may, for instance, occupy a position directly in front, and one directly in rear 70 of a preheating chamber of an incinerator, which is usually beneath the direct draft passage, to facilitate its segregation from other portions of the combustion chamber or control the products of combustion for the nu- 75 merous purposes that are obvious.

Each improved damper consists of a metal frame preferably of heavy quality pipe of wrought iron or steel provided with the vertical members 7-7, the lower cross member 8 80 and the intermediate cross member 9. These parts are usually coupled in the ordinary way by L and T members, said member 9 being provided with a union 10. The frame preferably extends the entire height of the combustion chamber of the incinerator and, when in lowered position, projects slightly above the upper surface thereof.

A bracing member or strut 11 consisting of two plates bolted together, spans the space 90 between the upper ends of the damper members 7-7 and maintain the same firmly in position. Said strut is also provided centrally with a bolt or other means for securing the lifting device which will be described later. 95

Extending from the upper end of one of the vertical side members 7, is a flexible armored tubing 12, in communication with the supply pipe 13 of the circulating system. Connected with the upper end of the other side member 7 of the damper is a flexible armored tubing 14 connected with piping 15 of said circulating system. Through tubular members 7, 8, 9, 12, 13, 14 and 15 is circulated water, as a cooling medium which is supplied in any preferred manner through pipe 16 then through pipe 13 and tube 12 and the frame and out through tubing 14, return pipe 15, and discharge pipe 17.

Mounted within the frame between cross 110

members 8 and 9 are the damper blocks 18 constructed of any preferred refractory material, said blocks are provided with grooves 19 at their ends in which tubular members 7 rest 5 when the parts are assembled. The lower block 18 is also provided with a groove 21 to fit over tubing 8; said grooves align the blocks or firmly retain them in place.

In the construction shown each frame is 10 usually mounted in a groove or recess 22 in the masonry. Said method protects the metal parts from direct blast of the heated gases and makes it possible to extend the blocks and fire resisting material entirely across the opening.

15 As a means for conveniently handling each damper in its movement up and down in the recess 22, either for repair purposes or for controlling the draft, a column 23 as shown in dotted outline, may be mounted in such a position as to carry a beam 24 on which is mounted sheaves 25 and 26. Over said sheaves a flexible cable 27 extends and is provided at one end with a counter weight 28 and is at its other end secured to the strut 11 preferably by 20 coupling 29 and link 30. Said link 30 is secured by bolt at 31 to the center of the strut 11.

A removable plate 32 is provided at the upper end of the frame to close the upper end of the channels and confine the gases of the 30 furnace.

In operation the damper here described may occupy an upper or a lower position within the furnace or be entirely removed for repair purposes. Blocks 18, notwithstanding 35 the fact that this system provides a cooling medium, do eventually disintegrate and require replacement, but such work can be quickly accomplished by removing the damper, uncoupling member 9, and swinging members 7 in opposite directions by swinging them in opposite parallel directions at which time old blocks can be readily removed and new blocks inserted.

40 By reference to Figs. 1 and 2, upright 45 guide members 35 are shown, said guides are provided for withdrawing the dampers entirely clear of the furnace for repair purposes. The counterbalance mechanism for the dampers will be seen in dotted outlines in Figs. 2 and 3 and are arranged centrally, only one-half of the parts being shown in Fig. 2, there

being only one of the guides shown in said Fig. 2.

Having thus described my invention, what I claim as new and desire to secure by Letters 55 Patent is:

1. A water cooled damper for incinerators or the like, having a hollow frame consisting of a pair of hollow side members, connected by a hollow cross member at their lower ends, 60 fire brick consisting of a plurality of members extending across the frame above the cross member and having grooves at their ends to engage said hollow side members, a hollow cross member arranged immediately above the fire clay members and communicating with said hollow side members, and made up of complementary parts joined by a union to enable adjustment of the parts for the replacement of the fire brick, a flexible water supply 65 pipe secured to the upper end of one of the side frame members and connected with a supply of water, a flexible discharge pipe secured to the upper end of the other vertical frame member adapted to return the cooling water, 70 a strut connecting the upper ends of the side members and means for attaching a suspending 75 device to said strut.

2. A water cooled damper for incinerators or the like, having a hollow frame consisting 80 of a pair of vertical side members connected by a hollow cross member at their lower ends, a plurality of horizontally arranged fire clay members extending across the frame above said cross member resting one upon the other 85 and having end grooves adapted to receive the vertical members of the hollow frame, a hollow cross member immediately above the fire clay members and communicating with said hollow side members and made up of complementary parts joined by a union to enable the separation of the parts for the replacement of the fire brick, a flexible water supply pipe secured to the upper end of one of the vertical frame members connected with the supply of 90 water, a flexible supply pipe secured to the upper end of the other vertical frame member adapted to return the cooling water, a strut connecting the upper ends of the side members and means for attaching a suspending 95 device to said strut.

EDGAR BOYD KAY.
